CLAIM

The ornamental design for a desktop caddy, as shown and described.

DESCRIPTION

FIG. 1 is a front perspective view of a desktop caddy showing our new design;

FIG. 2 is a front view of the desktop caddy in FIG. 1;

FIG. 3 is a rear view of the desktop caddy of FIG. 1;

FIG. 4 is a top view of the desktop caddy of FIG. 1; and,

FIG. 5 is a bottom view of the desktop caddy of FIG. 1.
